UNITED STATES PATENT OFFICE

104,385

DESIGN FOR A WIRE DOOR RACK

Harley R. Wall, Detroit, Mich., assignor to The Sparks-Withington Company, Jackson, Mich., a corporation of Ohio

Application March 10, 1937, Serial No. 68,090

Term of patent 3½ years

To all whom it may concern:

Be it known that I, Harley R. Wall, a citizen of the United States, residing at Detroit, in the county of Wayne and State of Michigan, have invented a new, original, and ornamental Design for a Wire Door Rack, of which the following is a specification, reference being had to the accompanying drawing forming part thereof,

The figure is a perspective view of a wire door rack showing my new design.

I claim:

The ornamental design for a wire door rack as shown,

HARLEY R. WALL.
